[57] CLAIM

The ornamental design for dial face for electronic display timepiece, substantially as shown and described.

DESCRIPTION

FIG. 1 is a front elevation of a dial face for electronic display timepiece showing my new design;

FIG. 2 is a front elevation thereof shown in an alternative position;

FIG. 3 is a front elevation thereof shown in an alternative position;

FIG. 4 is a front elevation thereof shown in an alternative position;

FIG. 5 is a front elevation thereof shown in an alternative position;

FIG. 6 is a front elevation thereof shown in an alternative position;

FIG. 7 is a front elevation thereof shown in an alternative position;

FIG. 8 is a front elevation thereof shown in an alternative position;

FIG. 9 is a front elevation thereof shown in an alternative position;

FIG. 10 is a front elevation thereof shown in an alternative position;

FIG. 11 is a front elevation thereof shown in an alternative position; and

FIG. 12 is a side elevation thereof.

The undisclosed rear view is plane and unornamented.
